NITRIC ACID OXIDATION OF SULFATED
FATTY MATERIALS

Francis J. Sprules, Arlington, and Richard Griffith, Fair Haven, N. J., assignors to Nopco Chemical Company, a corporation of New Jersey

No Drawing. Application July 6, 1944,
Serial No. 543,735

5 Claims. (Cl. 260—406)

1

The present invention relates to the nitric acid oxidation of sulfated fatty materials. More particularly, the present invention relates to the nitric acid oxidation of unsaturated acids and/or derivatives thereof and particularly to fatty acid esters which have been previously sulfated.

In U. S. application Serial No. 415,086, filed October 15, 1941, now Patent No. 2,365,290, granted December 19, 1944, a method for the oxidative scission of unsaturated fatty acids is disclosed. More particularly, the aforementioned application discloses a method for oxidizing an unsaturated fatty acid such as oleic acid so as to produce therefrom mono and dicarboxylic acids generally corresponding in length to the length of the chain on each side of the double bond. Preferably, as pointed out in the above application, the catalyst used is a manganese compound which provides greater yields than any of the catalysts previously known in the art.

As pointed out in the aforementioned application, greater yields are obtained when hydroxy acids are utilized rather than the original unsaturated acid. Thus, for example, yields in excess of 60% of the dibasic acid are produced when the unsaturated acid itself is used and yields in excess of 70 or 80% of the theoretical are produced when hydroxylated fatty materials are reacted. As may be understood, hydroxylated materials must be ordinarily prepared from the original unsaturated acid by various methods and even though the yields are higher, this is offset by the relatively complicated method necessarily followed in initially preparing the hydroxylated fatty material.

It has now been discovered that yields corresponding to those derived from the hydroxylated fatty materials and substantially in excess of those derived by oxidative scission of the original unsaturated acid may be prepared if sulfated fatty acids are subjected to oxidation. This is all the more surprising since ordinarily it would not be expected that sulfated fatty acids would be quantitatively hydrolyzed in situ and then oxidized by means of nitric acid to produce the mono and dibasic scission products.

It is one of the objects of the present invention, therefore, to provide a simple and economical process for the preparation of oxidative scission products of unsaturated fatty materials.

A second object of the present invention is to provide an improved process for oxidizing unsaturated fatty residues such as fatty acids and/or esters thereof, whereby unsaturated fatty acids and/or esters thereof are sulfated and are

subsequently oxidized in the presence of a catalyst—preferably a manganese compound.

Other objects and advantages of the present invention will become apparent from the present specification and claims.

In general, the sulfation of the fatty acids is carried out by treating the fatty acid or fatty material with 98% sulfuric acid for about 1/2 hour to an hour and thereafter washing the reaction mixture with cold salt solution to remove the excess. The aqueous layer is then separated and the fatty layer oxidized with nitric acid as particularly set forth hereinafter.

It has been discovered that the yields of scission products are to some extent dependent on the extent of sulfation. In general, the yields of scission products are higher when esters of the fatty acids are used rather than the fatty acids themselves. Preferably, these esters are the lower aliphatic esters such as the methyl and ethyl esters of the fatty acids, but other esters may be used and preferably the lower aliphatic esters, so long as the presence of the aliphatic group does not give rise to a solid or highly viscous compound which it would be difficult to sulfate.

After the sulfated product is prepared, the catalyst and nitric acid are added, usually while stirring and over a substantial period of time. Preferably, the nitric acid should be added extremely slowly, at least during an initial induction period. The mixture is then heated to a temperature between 25 and 110° C. and preferably between 90 and 110° C. This temperature is preferably maintained for from 2-12 hours, after which the reaction mass may be cooled or steam may be blown in and distillation of the monocarboxylic acids started. The steam distillation is carried on until no more monocarboxylic acids are driven off. Thereafter, the monobasic acid may be purified by extracting the same from the steam distillate with a suitable solvent such as hot dry ethylene dichloride. Other suitable solvents such as benzene, chloroform, ether, etc. may also be used.

The residue from the steam distillation is adjusted to a pH between 7 and 8 with caustic soda or other suitable base, and the aqueous layer produced is removed and treated with dilute sulfuric acid until it is acid to methyl orange (pH less than 4). It is then cooled to approximately 0° C. or any other suitable temperature to quantitatively precipitate dicarboxylic acids and the precipitated dicarboxylic acids then filtered.

The dibasic acids may also be recovered from

2

the steam distillation residue by any other suitable process such as a selective solvent extraction process. For instance, the residue may be extracted first with a nonpolar, or relatively slightly polar solvent such as a petroleum fraction to remove the unreacted oil and by-products without dissolving the dibasic acids. Thereafter, the residue may be extracted with a relatively more highly polar solvent, such as ethyl acetate, to dissolve the dibasic acids. Upon evaporation of the polar solvent extraction solution, the dibasic acids are left as a technically pure product. This product may be further refined and purified by recrystallization or other means.

A petroleum fraction was cited above as a suitable non-polar solvent; however, ethylene dichloride, chloroform, cold benzene, cold ether and other solvents of like character may be employed. Ethyl acetate was cited as a suitable relatively highly polar solvent; however, butanol, hot water, hot methanol, hot ethanol, hot ether or the like may be substituted therefor.

The dicarboxylic acid and monocarboxylic acids may also be separated by other means than steam distillation. Thus the oxidized mass may be treated and extracted with caustic soda solution to form the relatively soluble monosodium salt of the dicarboxylic acid. The residue may then be distilled to purify the monocarboxylic acid. Preferably, an amount of approximately 3% of catalyst is used in the above reaction, although from 1/10 to 5% may be used with relatively good results. It is to be noted that the amount of catalyst is not critical and quantities greater than 5% may be employed. The amount of nitric acid employed should be somewhat greater than the amount theoretically required to cut the fatty chains and oxidize the carbon atoms at the point of scission to carboxyl groups, i. e. greater than 4 mols per mol of fatty material.

The strength of nitric acid employed should be greater than about 60% and should preferably be commercial concentrated nitric acid having a strength between about 65% and about 71%, although fuming nitric acid may be employed. In general, the preferred catalyst for the present oxidation reaction is a manganese compound which may be selected from the group consisting of a manganous or manganic salt or manganese oxide or any salt of a manganese-containing acid radicle. Examples of suitable manganese compounds coming within these requirements are the manganese oxides and manganese salts of which manganese chloride, manganese nitrate, manganese oxide, manganic oxide, manganese trioxide, manganese heptoxide, potassium permanganate, sodium manganite, manganese stearate, etc., may all be particularly mentioned. However, other oxidation catalysts have been found suitable, although the yields are not as great as those produced by the use of the manganese catalyst. Thus, nickel compounds and vanadium compounds are suitable and compounds of other metals having similar characteristics such as chromium, cobalt, iron, and copper. Compounds of other catalytic metals such as molybdenum, rhodium, palladium, silver, tantalum, tungsten, iridium, platinum, and gold may be used. These metals are all characterized by having at least 2 incomplete outer electronic orbits in the atomic state. They are the metals of group Ib or groups Va, VIa, VIIa, and VIII in the so-called long series of the periodic table of Mendeleef.

Typical compounds of these metals of use in

this connection are the soaps, oxides, and salts, such as the halides, sulfates, nitrates, phosphates, etc. Other compounds such as the chromates, dichromates, vandadates, permanganates, managanates, manganites and molybdenates in which the metal is a constituent of the anion are suitable. Other complex salts such as the chloroplatinates, aurichlorides, etc. are also useful in this connection.

10 The present invention is applicable to any of the fatty acids or fatty acid derivatives having an unsaturated bond or its equivalent. Thus, oils, fats, fatty acids, or fatty esters containing fatty chains having unsaturated groupings intermediate the end of such chains are suitable (although preferably, the present process is practiced with esters of such fatty acids). Examples of suitable unsaturated acids are oleic acid, brassidic acid, erucic acid, linoleic acid, eleostearic acid, linolenic acid, clupanodonic acid, 20 and esters thereof such as methyl oleate, ethyl oleate, methyl palmitoleate, etc. Instead of the pure acids, mixed acids may be employed which may be derived from the naturally occurring fats and oils, as, for example, castor oil, olive oil, sardine oil and the like.

25 The following examples serve to illustrate but are not intended to limit the invention.

Example I

30 50 grams of methyl oleate were sulfated for 20 minutes at a temperature of from 0-5° C. with 30 grams of 98% sulfuric acid. The sulfated mass was then stirred for half an hour, poured into 35 120 cc. of a water and ice mixture containing 20 grams of sodium chloride and the aqueous layer allowed to separate and drawn off. The aqueous layer was removed and the fatty layer heated to 110° C. with 1 gram of manganese 40 dioxide. 140 cc. (200 grams) of concentrated nitric acid were then run in with stirring over a period of 6 hours. The mixture was then heated further for 6 hours at 115-120° C. (oil bath temperature) and then distilled with stirring while 200 cc. of water in the form of steam 45 were slowly added. The steam distillate was saturated with sodium chloride, ether extracted and dried. Removal of the ether from the extract left 11.5 grams of pelargonic acid. The residue from the steam distillation was then 50 made alkaline with sodium hydroxide to a pH of 7-8, benzene extracted and the aqueous layer acidified with hydrochloric acid to a pH of somewhat less than 4. White solids precipitated 55 which were filtered off and dried at 60° C. for 12 hours. The solid acid thus produced weighed 24 grams and had a neutral equivalent of 109 and corresponded to a yield of 76% of azelaic acid.

Example II

60 50 grams oleic acid were cooled to 0-8° and 30 grams 98% sulfuric acid added at that temperature as rapidly as possible with stirring. After 1/2 hour stirring, the mass was diluted with 120 grams of ice water containing 20 grams NaCl, 65 thoroughly mixed, and when the layers had separated, the aqueous wash waters were drawn off. The fatty layer, with 1 gram MnO₂ added thereto, was heated to 110° and a total of 140 cc. by volume or 200 grams by weight HNO₃ (d=1.42) 70 added with stirring. About 1/6 the total volume of HNO₃ was added rapidly at first. The addition of acid was then stopped during a brief induction period of about 1/2 hour. When brown fumes began to evolve and foaming started, care-

ful addition of the rest of the acid was made. Approximately 6 hours total time was required for addition of HNO_3 . The reaction mixture was then refluxed with stirring for 4 hours more and steam distilled directly until no more monocarboxylic acids were driven off.

The steam distillate was treated with salt and extracted with dry ethylene dichloride. Removal of ethylene dichloride left 12 grams of pelargonic acid.

The residue from steam distillation was adjusted to pH 7-8 with 23.5% NaOH and the layers allowed to separate. The aqueous layer was then removed, made acid to methyl orange with dilute H_2SO_4 cooled to 0° C. and filtered. Air drying of the cake yielded 22 grams azelaic acid, neutral equivalent 106 or 73% of theory.

Having described our invention, what we claim as new and desire to be secured by Letters Patent is:

1. A process for oxidizing unsaturated fatty residues comprising sulfating said residues, treating the sulfated residue with nitric acid in the presence of an oxidation catalyst and separating the mono and dicarboxylic acids produced.

2. A process for oxidizing unsaturated fatty residues comprising sulfating said residues, treating the sulfated residue with nitric acid in the presence of a manganese compound selected from the group consisting of manganese oxides and manganese salts and separating the mono and dicarboxylic acids produced.

3. A process for oxidizing methyl esters of unsaturated fatty acids to produce mono and dicarboxylic acids comprising sulfating said methyl ester and then treating the sulfated methyl ester with nitric acid in the presence of an oxidation catalyst.

4. A process for oxidizing unsaturated fatty acid esters comprising sulfating said fatty acid esters, treating the sulfated fatty acid ester with nitric acid in the presence of an oxidation catalyst and separating the mono and dicarboxylic acids produced.

5. A process for oxidizing unsaturated fatty acid esters comprising sulfating said fatty acid ester, treating the sulfated fatty acid ester with nitric acid in the presence of a manganese compound selected from the group consisting of manganese oxides and manganese salts and separating the mono and dicarboxylic acids produced.
